Primary Examiner — David Muller*Assistant Examiner* — Nathan Johnston(74) *Attorney, Agent, or Firm* — GrayRobinson, PA;
Donald S. Showalter(57) **CLAIM**

The ornamental design of an advertising device for dispensing sanitizing articles, as shown and described.

DESCRIPTION

FIG. 1 is a perspective view of an advertising device for dispensing sanitizing articles showing our new design; FIG. 2 is a second perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.
The broken lines form no part of the claimed design.

1 Claim, 7 Drawing Sheets
